UNITED STATES PATENT OFFICE

153,208

DESIGN FOR A MERCHANTISING DISPLAY
AND STORAGE CABINET

John J. Corrigan, Elmhurst, N. Y., assignor to David E. Kennedy, Inc., Brooklyn, N. Y., a corporation of New York

Application January 23, 1948, Serial No. 144,007

Term of patent 14 years

(Cl. D80—11)

To all whom it may concern:

Be it known that I, John J. Corrigan, a citizen of the United States of America, and a resident of Elmhurst, Queens County, State of New York, have invented a new, original, and ornamental Design for a Merchandising Display and Storage Cabinet, of which the following is a specification, reference being had to the accompanying drawing, forming a part thereof.

In the drawing, the figure is a perspective view of the merchandising display and storage cabinet, showing my new design.

The side of the cabinet not shown is the same in appearance as is the side shown, and the back of the cabinet is substantially plain.

I claim:

The ornamental design for a merchandising display and storage cabinet, substantially as shown and described.

JOHN J. CORRIGAN.
